UNITED STATES PATENT OFFICE.

LLOYD ESPENSCHIED, OF QUEENS, NEW YORK, ASSIGNOR TO AMERICAN TELEPHONE AND TELEGRAPH COMPANY, A CORPORATION OF NEW YORK.

HIGH-FREQUENCY MULTIPLEX SIGNALING SYSTEM.

Original application filed September 30, 1919, Serial No. 327,500. Divided and this application filed April 16, 1921. Serial No. 461,966.

To all whom it may concern:

Be it known that I, LLOYD ESPENSCHIED, residing at Queens, in the county of Queens and State of New York, have invented certain Improvements in High-Frequency Multiplex Signaling Systems, of which the following is a specification.

This invention relates to high frequency multiplex signaling system and more particularly to a terminal circuit arrangement embodying the use of a common translating circuit adapted both to modulate the transmitted current and to demodulate the high frequency received current.

15 This application is a division of my co-pending application Serial No. 327500 filed September 30, 1919, entitled high frequency multiplex signaling systems.

In the multiplex signaling systems heretofore used which employ a plurality of carrier currents of various frequencies, it has been customary to insert in the transmitting and the receiving branches of the terminal circuit a translating device individual to each of said branches. It is the object of the present invention to adapt the terminal circuit arrangement so that the processes of modulation, demodulation and amplification of the various currents in both the transmitting and receiving branches of the terminal circuit may be performed by a single translating device. Although the preferable form of translating device is a single thermionic vacuum tube or a plurality of such tubes in combination adapted to function as a single unit with respect to the two branches of the terminal circuit, yet any well known type of translating device such as the mechanical repeater may be used.

40 Another object of this invention is to provide a circuit arrangement of the general character described above in which the filters are inserted in the two-wire circuits, that is to say between the line circuits and the triple winding transformer which serves to connect the common translating circuit with the two-wire signaling circuits.

Other and further objects of this invention will be apparent from the following 50 description when read in connection with the attached drawing of which Figure 1 shows an arrangement employing two triple winding transformers in which the third

winding of each transformer is connected in parallel with the output circuit of the translating circuit; and Figure 2 shows an arrangement in which a single triple winding transformer is used which is arranged for the transformation of both the high frequency and the low frequency currents.

55 Figure 1 shows a variation of the type of circuit described in my copending application referred to hereinbefore, in which a single translating unit performs both functions of modulation and demodulation for the two sides of the circuit, the variation consisting in the placing of the high frequency and the low frequency filters in the two-wire portions as distinguished from the four-wire portion of the circuit. The circuit arrangement shown in the upper part of this figure represents one of the terminal circuits for the reception or transmission of one of the bands of frequencies based upon a definite carrier frequency, which may be 60 transmitted or received over the main transmission circuit ML. In the circuit arrangement L_1 represents a low frequency signaling circuit, which is connected with the windings of the triple winding transformer T_1 and is balanced by the network N_1 . Interposed between the line L_1 and the said transformer, and the network and the said transformer, are low frequency band filters F_1 and F_2 . The high frequency line L_3 is connected with the windings of another triple winding transformer T_2 with which is connected a balancing network N_3 adapted to balance the high frequency line. Interposed between the line L_3 and the said transformer, 65 and the network N_3 and the said transformer, are the high frequency band filters F_3 and F_4 respectively. The midpoints of two of the windings of each transformer, T_1 and T_2 , connected with lines L_4 and L_5 , are connected in parallel, the said connection embracing one of the windings of the transformer T_3 . The third windings of the transformers T_1 and T_2 are connected in parallel, the said connection embracing one of the windings of the output transformer T_4 of the translating circuit. Inductances C_1 and C_2 are inserted in the conductors connecting the said third windings of transformers T_1 and T_2 with the output transformer T_4 in order to prevent the passage of

high frequency oscillations between the transformer T_1 and T_2 .

In the operation of this circuit low frequency voice currents from line L_1 will pass through the low frequency band filter F_1 and will be impressed across the midpoints of the windings of the coil T_1 with which the line L_1 is connected. These signaling currents will in turn be impressed by the coil 1 of the input transformer T_3 upon the coil 2 of the said transformer, and will accordingly modulate the high frequency oscillations which are impressed upon the translating circuit by the source 3. The modulated high frequency oscillations will pass through the output transformer T_4 and will be impressed by the winding 4 of the transformer T_2 upon the high frequency circuit L_3 . The high frequency currents are excluded from the low frequency circuit by inductances C_1 and C_2 and filters F_1 F_2 . The high frequency modulated waves will pass through the high frequency band filter F_3 to the main transmission line ML , and thence to the terminal circuit at the opposite end of the said line. The modulated high frequency oscillations received over the transmission line ML will be conducted by the circuit L_3 through band filter F_3 to the midpoint of the windings of transformer T_2 . These oscillations will be impressed across winding 1 of transformer T_3 and will pass through the translating device and be demodulated thereby. The low frequency demodulated current will pass through inductances C_1 and C_2 which offer substantially no impedance to low frequencies, to the winding 6 of transformer T_1 and will be impressed upon the low frequency line L_1 passing through the band filter F_1 . The low frequency currents are excluded from the high frequency circuit by condenser 5 and the high pass filters F_3 F_4 .

This circuit arrangement illustrates a method by which the high frequency and the low frequency currents may be impressed upon a common translating device by means of balancing coils which are connected effectively in parallel. It should be understood that any number of terminal circuits similar to the one described may be connected with the main transmission line, the terminal circuits being made selective by the insertion in each branch high frequency circuit of a band filter similar to F_3 but adapted to transmit any desired band of frequencies for the specific terminal circuit. Furthermore, a low frequency signaling circuit L_5 might be connected with the transmission line through a suitable low frequency filter F_5 for the transmission of low frequency signaling current over the transmission line simultaneous with the transmission of the various bands of high frequency oscillations.

Figure 2 shows another variation of the

general type of circuit which differs from the circuit arrangement shown in Figure 1, in that the low frequency and the high frequency transformers are connected mutually in series instead of in parallel as shown in Figure 1. These two transformers may be replaced by one transformer suitably designed to efficiently transmit both high and low frequencies. The coils designated a and a' represent the low frequency transformer and the coils designated b and b' represent the high frequency transformer. Another distinguishing characteristic consists in the use of a single balancing network N adapted to balance the high frequency line which may be connected with a plurality of terminal circuits.

In the figure, L_1 represents a low frequency line, having inserted therein a low frequency band filter F_1 , and connected with two of the windings of the triple winding transformer T_1 . L_3 represents a high frequency branch circuit having inserted therein a high frequency band filter F_3 , and connected with the opposite ends of the same two windings of the transformer T_1 with which the line L_1 is also connected. The midpoints of the said two windings of transformer T_1 are connected with the coil 1 of the input transformer T_3 , the other coil of which is connected across the input side of the duplex translating circuit. The output side of the said circuit is connected by means of the transformer T_4 with the third winding of the said transformer T_1 . Bridged across the circuit L_3 between the filter F_3 and the point of connection of the said circuit with the transformer T_1 is a balancing circuit containing low frequency filter F_2 and network N_1 , which is adapted to balance the low frequency line L_1 . Bridged across the circuit L_1 between the filter F_1 and the point of connection with the windings of the transformer T_1 is a balancing circuit containing high frequency filter F_4 and the network N_2 , which is adapted to balance the main transmission line ML with respect to a plurality of terminal networks.

In the operation of this circuit low frequency currents are received over the line L_1 and will pass through the filter F_1 and be impressed upon the coil 1 of transformer T_3 . The high frequency oscillations from the source 3 will be modulated in accordance with the low frequency signaling currents by the duplex translating circuit. The modulated high frequency oscillations will be impressed by means of transformer T_4 upon the third winding of the transformer T_1 , and will set up similar oscillations in the circuit containing the other two windings, which will pass through the high frequency filter F_4 , over the high frequency circuit L_3 , to the main transmission line ML . These high frequency oscillations can-

- not pass into the low frequency line L_1 since the filter F_1 is adapted to transmit only low frequency currents. In a similar manner the received high frequency oscillations arriving over the line L_3 will pass through the high frequency band filter F_2 (assuming that they are within that band of frequencies which this filter is adapted to pass) and will be impressed across the 5 coil 2 of transformer T_3 . These high frequency oscillations will combine with the unmodulated carrier oscillations from the source 3, and will be demodulated in the translating circuit. The low frequency 10 currents derived thereby will be transmitted by the transformer T_4 to the third winding of the transformer T_1 , and will be impressed upon the receiving circuit connected with the other two windings of the transformer. 15 These low frequency currents will pass through the filter F_1 into the low frequency line L_1 and actuate the low frequency signaling apparatus associated therewith. These low frequency oscillations will not 20 pass back into the high frequency circuit L_3 , since the filter F_3 , which is interposed between the two circuits, is not adapted to pass low frequency currents. It will be seen therefore that this circuit arrangement 25 provides means whereby the modulation of the transmitted waves and the demodulation of the received waves may be performed by a single translating circuit, which is connected with a single two-wire circuit by 30 means of a single triple winding transformer. Furthermore, this circuit arrangement shows a method whereby a single network may be utilized with a plurality of terminal circuits to balance the main transmission line with which the plurality of 35 terminal circuits may be connected.

Since the circuit is balanced with respect to the conjugate transformer by means of the networks which are designed to approximate electrically the line circuits connected with the end of the transformer opposite that to which the network is connected, the translating circuit may be operated so as to give greater amplification than the loss 50 within the circuit itself without producing singing around the circuit.

Although this invention has been disclosed as being embodied in a particular form and arrangements of parts it is to be understood that it is capable of embodiment in other and different forms without departing from the spirit and scope of the appended claims.

- What is claimed is:
1. In a signaling system, the combination with a high frequency transmission circuit, of a low frequency signaling circuit, and a translating circuit interlinking said transmission and said signaling circuits and having means common to the transmitting 60

and receiving paths of the oppositely traveling currents from said transmission circuit and said signaling circuit to modulate the currents from the said signaling circuit and to demodulate the currents from the said transmission circuit and means to impress the modulated and demodulated currents upon the transmission and the signaling circuits respectively. 70

2. In a signaling system, the combination with a high frequency transmission line having a high frequency band filter and a balancing network connected therewith, of a low frequency circuit having a low pass filter and a balancing network, a translating circuit common to the said high frequency line and low frequency circuit, and means to impress currents from the said high frequency line and the said low frequency circuit upon the said translating circuit, the 80 said translating circuit having means to modulate and demodulate the impressed currents. 85

3. In a signaling system, the combination with a high frequency circuit having high frequency band filters and a balancing network associated therewith, of a low frequency circuit having low pass filters and a balancing network associated therewith, a translating circuit common to both the high frequency and the low frequency circuit, a transformer connecting the said high frequency and the low frequency circuit with the input and the output sides of the said translating circuit, the said translating circuit having means to modulate and demodulate the currents from the said low frequency and the said high frequency circuits respectively. 90 95 100

4. In a signaling system, the combination with a high frequency circuit of a low frequency circuit, a translating circuit having a frequency changing device connected therewith, a conjugate transformer coupling the said high frequency and the said low frequency circuits to the said translating circuit, and a high frequency band filter and a low pass filter inserted in the said high frequency and the said low frequency circuits respectively between the said circuits 110 and the said transformer. 115

5. In a signaling system, the combination with a high frequency circuit of a low frequency circuit, a translating circuit, a conjugate transformer connecting the said high frequency and the said low frequency circuits to the said translating circuit, the said transformer having a plurality of windings each containing a high frequency and a low frequency coil in series for the 120 transformation of high frequency and low frequency currents. 125

6. In a high frequency signaling system, the combination of a source of low frequency signaling current, a source of high 130

frequency current, a translating circuit having means common to the transmitting and receiving paths of the oppositely traveling currents from the said sources to modify both the transmitted and received currents, means for impressing the said currents upon the said translating circuit and frequency selecting means associated with the said source of signaling current and the said source of high frequency current whereby interference between the respective sources is prevented.

7. In a high frequency signaling system, the combination of a low frequency signaling circuit, a high frequency transmission circuit, a translating circuit having common means to modulate and demodulate the transmitted and received currents respectively, high frequency and low frequency transforming means connected mutually in series for impressing said currents upon said translating circuit, and frequency selecting means associated with the said signaling circuit and said high frequency circuit whereby interference between the respective circuits is prevented.

8. A duplex system comprising a low frequency line, a high frequency circuit, a modulator-detector circuit adapted to modulate currents passing in one direction between said line and said circuit and to detect currents passing in the other direction there between, a transformer coupling the said low frequency line and the said high frequency circuit to the said modulator-detector circuit, a network for balancing the low frequency line and a filter for reducing the passage of high frequency currents to the said network.

9. A duplex system comprising a low frequency line, a high frequency circuit, a modulator-detector circuit adapted to modulate currents passing in one direction between said line and said circuit and to detect currents passing in the other direction there between, a transformer coupling the said low frequency line and the said high frequency circuit to the said modulator-detector circuit, a network for balancing the high frequency line and a filter for reducing the passage of low frequency currents to the said network.

10. In a carrier current system, a hybrid

coil and a low pass filter and a high pass filter connected in parallel to one terminal 55 of the said coil.

11. In a carrier current system, a hybrid coil, a low pass filter and a high pass filter connected to one terminal of the said coil and a high pass filter and a low pass filter 60 connected to the other terminal of the said coil.

12. In a carrier current system, a high frequency line and impedance means for balancing the said line, a high pass filter 65 connecting the said impedance means to the said line, a hybrid coil and a second high pass filter.

13. In a carrier current system, a high frequency line, a low frequency line, means 70 connecting said lines comprising a low pass filter adjacent said low frequency line, a high pass filter adjacent said high frequency line, a hybrid coil between said filters, a branch circuit containing a high pass filter 75 and a balancing network for said high frequency line connected between said low pass filter and said hybrid coil, a second branch circuit containing a low pass filter and a low frequency balancing network connected 80 between said first mentioned high pass filter and said hybrid coil and a detector having its input circuit coupled to said hybrid coil and its output circuit coupled thereto in conjugate relation with respect to the said 85 first coupling.

14. In a carrier current system, a high frequency circuit, a low frequency circuit, a single repeating device connected to said circuits to repeat low frequency currents 90 from said low frequency circuit as high frequency currents to said high frequency circuit and to repeat high frequency currents from said high frequency circuit as low frequency currents to said low frequency circuit and individual balancing means connected with the said high frequency and the said low frequency circuits at the points of connection of said circuits with the said repeater for simulating the impedances of 95 both the said circuits.

In testimony whereof, I have signed my name to this specification this 15th day of April 1921.

LLOYD ESPENSCHIED.
